UNITED STATES PATENT OFFICE.

IVAN KING, OF LOS ANGELES, CALIFORNIA.

REEL-OVEN.

1,372,144.

Specification of Letters Patent. Patented Mar. 22, 1921.

Application filed April 22, 1918. Serial No. 230,121.

To all whom it may concern:

Be it known that I, IVAN KING, a citizen of the United States, residing at Los Angeles, in the county of Los Angeles and 5 State of California, have invented a new and useful Reel-Oven, of which the following is a specification.

My invention relates to bakers' ovens, being more particularly the type of oven commonly termed a reel oven which is used for the purpose of baking cookies, crackers, cakes, bread and similar articles. Ovens of 10 this type are generally constructed with the door of the oven arranged in the wall of the oven adjacent to the nearest point of the reel to the wall, which places the door approximately half way between the top and the bottom of the reel. In opening the door of 15 an oven so constructed it will be readily understood that the heat of the oven, particularly the heat in the lower half of the oven, will very quickly pass out of the door thereby lowering the temperature of the oven to a great extent.

20 The principal object of my invention is to produce an oven of the class described, of simple form and construction, in which the door of the oven is placed at or below the lowest portion of the reel and in line with or 25 below the floor of the oven.

Other objects and advantages will appear hereinafter from the following description.

Referring to the drawings, which are for 30 illustrative purposes only,

Figure 1 is a vertical sectional view of an oven embodying a form of my invention.

Fig. 2 is a front elevation of the oven shown in Fig. 1 on a reduced scale, a portion of the face of the oven being broken 40 away to show the interior thereof.

Fig. 3 is a diagrammatic view of an oven embodying another form of my invention.

11 designates an oven, 12 the front wall, 13 the rear wall and 14 a curved top wall. 45 15 designates the floor of the oven having a series of openings 16 formed therein communicating with the fire box 17 formed under the floor of the oven. 18 designates the door of the fire box through which extends an oil burner 19, and 20 designates a flue connecting with the stack 21.

Extending through the oven and supported in suitable bearings 22 in the side walls of the oven is a shaft 23 upon which

is secured two large sprocket wheels 24 55 forming the reel. These sprocket wheels 24 support an endless carrier which consists of sprocket chains 25, between which chains are pivotally supported a series of trays 27 which extend across from one chain 25 to 60 the chain 25 on the opposite sprocket wheel.

A loop 30 is formed in each chain 25 by extending the chain forwardly as shown in Fig. 1 over a smaller sprocket wheel 31, an idler 32 being provided for guiding the return or upper portion of the loop to the sprocket wheel 24. The front wall 12 of 65 the oven is extended forward as indicated at 34 and is provided with a door 35 through which access is had to the interior of the oven. 36 designates a glass plate or window through which the interior of the baking chamber of the oven may be inspected.

40 designates a gear wheel secured to the shaft 23 on the outside of the oven which is 75 driven by a spur gear 41 from a motor 42 thereby driving the chains and carrying the trays therewith through the oven.

The oven is operated by setting the motor in operation which drives the shaft 23 80 through the connections heretofore described thereby driving the sprocket wheels 24 and chains thereon which carry the trays through the path of the sprocket chains in the direction of the arrow shown in Fig. 1. 85 As the trays on the lower run of the loop 30 approach the door 35 suitable pans carrying the material to be baked are placed upon the same as they pass the door opening, and when so placed travel upwardly to the 90 highest part of the oven and then continue to the lowest part of the sprocket wheel where they enter the loop and are brought forward to the door.

In the form shown in Fig. 3 the loop indicated at 50 extends downwardly from the sprocket wheels instead of forwardly, it being understood that a loop is formed in the carrier, that is, the sprocket chains, either at or below the main floor of the oven so that 100 the heat is not lost from the oven by reason of opening the door during the operation.

The oven chamber is formed with an extension in the forward part of the same and the door is in the front of such extension. 105 The loop in the chains extends into such extension away from the body of the oven chamber and toward the door. With this

construction the door does not expose the oven chamber proper nor directly disturb the heat therein.

What I claim is:—

- 5 1. An oven comprising an oven chamber, a door for the oven chamber, a rotatable reel in the chamber, an endless carrier supported on the reel, trays mounted on the carrier, and a loop formed in the carrier extending 10 away from the reel toward the door, the lower run of said loop extending tangentially forward from the lowest part of the reel.

2. An oven comprising an oven chamber an extension in the forward part of said chamber, a rotatable reel in the chamber, an endless carrier supported on the reel, trays mounted on the carrier, a loop formed in the carrier extending away from the reel into said extension, and a door in said extension through which the trays on the loop are accessible.

In testimony whereof, I have hereunto set my hand at Los Angeles, California, this 13th day of April, 1918.

IVAN KING.
